[57] CLAIM

The ornamental design for a breaker tool for hanging
file frame rails, as shown and described.

DESCRIPTION

FIG. 1 is a front elevational view of a breaker tool for
hanging file frame rails, showing my new design;

FIG. 2 is a view in top plan of the breaker tool;

FIG. 3 is a view in bottom plan of the breaker tool;

FIG. 4 is a view in side elevation of the breaker tool

looking from the left of FIG. 1;

FIG. 5 is a view in side elevation of the breaker tool
looking from the right of FIG. 1; and,

FIG. 6 is a view in rear elevation of the breaker tool.

FIG. 1

FIG. 2

FIG. 4

FIG. 3

FIG. 5
